UNITED STATES PATENT OFFICE.

JOSE MARCELINO URGELLÉS, OF NEW YORK, N. Y.

NON-REFILLABLE BOTTLE.

SPECIFICATION forming part of Letters Patent No. 655,641, dated August 7, 1900.

Application filed April 21, 1900. Serial No. 13,729. (No model.)

To all whom it may concern:

Be it known that I, JOSE MARCELINO URGELLÉS, of New York, in the county of New York and State of New York, have invented 5 a new and useful Improvement in Non-Refillable Bottles, of which the following is a specification.

My invention is in the nature of a non-refillable bottle designed to insure to the pur- 10 chasing the purity and genuineness of the contents originally placed therein, and which bottles when once emptied cannot be refilled with a spurious article.

It relates to that form of bottle in which 15 two balls are held in a valve-seat arranged to be locked in the neck of the bottle beneath the cork, the larger one of which balls acts as a valve to permit the outflow of liquid and the smaller of which balls acts as a back bearing to follow up and hold the larger ball to 20 its seat.

My invention consists in the peculiar construction and arrangement of the parts of the device for rendering it safer as against being 25 tampered with and for promoting cleanliness and certainty of action, as will be hereinafter fully described, reference being had to the accompanying drawings, in which—

Figure 1 is a vertical section of the valve- 30 casing and valve. Fig. 2 is a detached view of the spiral protecting cage or guard. Fig. 3 is a detached view of the conical runway for the smaller ball. Fig. 4 is a bottom end view of the valve-casing. Fig. 5 is a cross- 35 section on line 5 5 of Fig. 8. Fig. 6 is a top view of a protecting-shield for the valve mechanism. Fig. 7 is a side view of the valve-casing; and Fig. 8 is a sectional view of the neck 40 of the bottle with the valve-casing and valve, the shield, and the cork all in place.

In the drawings, A represents a short cylinder, of glass, wholly open at its upper end and having at its lower end a smaller opening bordered by an inwardly-projecting flange 45 forming a valve-seat for the ball-valve D. In the lower portion of this cylinder there are formed inwardly-projecting longitudinal ribs a, forming a runway or guide-rail for the ball-valve to roll on as the ball D rises from its 50 seat in the act of pouring out the liquid. The cylindrical valve-casing, with ribs a, are all formed of glass and in one piece. On the

top of the ribs a there is supported a conical cap B, also made of glass and permanently united to the ribs a by fusion. This conical 55 cap has a longitudinal slot b running through its side from end to end, through which the liquid passes from the valve to the space around the cone and within the cylinder. This cone B forms both a passage-way for the 60 liquid and a receiving-chamber for the small ball d, which forms the back bearing or follower to the valve-ball D. When the ball d rolls into the cone, it will be seen that the slot b will allow the liquid to pass out from the 65 cone, no matter what the position of the ball in the cone may be.

Around the cone B, of glass, there is arranged a spiral cage or coil C, also made of glass. This is permanently fixed in place by 70 being fused at its upper end to the projecting lugs b' on the top of the cone and is also rigidly secured at its lower end by fusion to the side walls of the cylindrical casing A. The object of this cage is to form a protecting- 75 guard which will prevent the reaching of the balls by a slender rod or wire and lifting them to refill the bottle.

The ball-valve D, of glass, is made relatively light in proportion to its bulk by being formed 80 hollow, as shown, so that its weight is only a little heavier than the same bulk of liquid, while the follower-ball d is much heavier in proportion to its size, being made of metal coated with a porcelain glaze or enamel. 85 When this follower-ball d rests upon the valve-ball, said ball d passes part the way between two adjacent ribs a a, as seen in Fig. 5, and thus wedges and holds the ball-valve more tightly, and at the same time is removed 90 to an eccentric position, so that it is less likely to be tampered with. The object in making the valve D hollow is to make it light and more sensitive in action and less likely to be jammed by its own weight, and the object in 95 making the follower-ball d relatively heavy is to give it good backing-up or holding power on the ball-valve and at the same time give it such small dimensions as to allow the liquid room to freely pass it and also to better 100 permit it to drop to an eccentric position between the ribs a.

To fix the valve in the neck of the bottle, the latter is made rather long and is formed on

its inner walls, near the lower end, with an inwardly-opening transverse groove g , as seen in Fig. 8. On the outer-surface of the lower end of cylindrical valve-casing there is formed a 5 surrounding groove a' , in which is laid a packing-strip of cork, soft-rubber, or a cotton string, which fitting closely to the walls of the bottle-neck makes a tight joint. Just above this groove in the cylindrical casing there is on 10 one side a hemispherical recess a^2 , forming a seat to receive a little cork or rubber cushion e , on which rests a little glass ball e , which is arranged to be pressed inwardly against the cork or rubber cushion e while the cylinder 15 A is being forced down the neck of the bottle, and which ball when it reaches the groove g in the neck of the bottle springs outwardly from its elastic backing and entering the groove g locks the valve-casing in the neck of 20 the bottle. Instead of making this locking device in the form of a ball it may be elongated transversely in the form of a curved bar e^2 , seated in a curved recess formed transversely in the casing, as seen in Fig. 5. Such locking 25 devices may be either upon one or both sides, as shown. There is a distinct function in making one of these locking devices in the form of an elongated curved bar e^2 and the other in the form of a ball e , for if two balls were 30 employed the valve-casing would be held at two diametrical points on pivots, and it would have a tendency to turn and chatter in transportation about such diametrical pivots. By making one in the form of a ball and the 35 other an elongated bar e^2 , curved transversely, the sensitive yielding of the ball makes the casing easy to insert and the long bearing of the curved bar e^2 prevents pivotal action and holds the casing firmly in place. 40 After the valve-casing has been locked in place in the bottle-neck, as described, a round shield E , Fig. 6, of enameled metal or any other non-corrosive material, is loosely placed upon the top of the valve-casing, and the 45 cork is then inserted above it, as seen in Fig. 8. This shield has a small loop-handle l , by which it may be removed. The object of such shield is to prevent accidental protrusion of the corkscrew below the cork from doing dam-

age to the valve-casing and its contained 50 part and to prevent particles of cork from falling into and obstructing the action of the valve.

Having thus described my invention, what I claim as new, and desire to secure by Letters 55 Patent, is—

1. The spiral coil C , combined with a ball-valve casing and a central conical cap, said spiral coil being arranged around the central conical cap and between its walls and those 60 of the valve-casing, substantially as and for the purpose described.

2. In a non-refillable bottle the combination with a valve-casing having a central conical chamber, of two balls both made of greater 65 specific gravity than the liquid contents, the larger ball being made of glass and hollow, and the smaller ball being made of metal and enameled substantially as and for the purpose described.

3. The combination with a bottle-neck having a transverse internal groove; of a valve-casing having in its exterior wall a recess upon each side one hemispherical and the other a curved transverse groove, an elastic 75 cushion and ball arranged in one, and an elastic cushion and curved locking-piece in the other substantially as and for the purpose described.

4. In a non-refillable bottle, the combination with the bottle-neck, a rigidly-locked valve-casing in the lower end of said neck and a cork in the upper end of the same; of a detachable transverse shield made of non-frangible material, said shield being formed 85 as a disk fitted transversely in the neck of the bottle between the cork and the valve-casing and filling the transverse space of the neck, and having on its upper side a loop-handle for effecting its withdrawal substantially as described.

In testimony whereof I have signed my name to this specification in the presence of two subscribing witnesses.

JOSÉ MARCELINO URGELLÉS.
